UNITED STATES PATENT OFFICE

107,903

DESIGN FOR AN AIRPLANE

**Fredric E. Flader, Kenmore, N. Y., assignor, by
mesne assignments, to Curtiss-Wright Corpora-
tion, a corporation of New York**

Application May 26, 1936, Serial No. 62,837

Term of patent 14 years

To all whom it may concern:

Be it known that I, Fredric E. Flader, a citizen of the United States, residing at Kenmore, in the county of Erie and State of New York, have invented a new, original, and ornamental Design for an Airplane, of which the following is a specification, reference being had to the accompanying drawing, forming part thereof.

Fig. 1 of the drawing is a perspective view of an airplane embodying the new design as it would appear from a point forward and above the airplane when in flight with its landing wheels retracted;

Fig. 2 is a plan view of the airplane;
Fig. 3 is a front elevation of the subject airplane shown in the other figures; and

Fig. 4 is a side elevation of the airplane in which its landing wheels are also shown in the retracted position as in the other figures.

I claim:

The ornamental design for an airplane substantially as shown and described.

FREDRIC E. FLADER.
